UNITED STATES PATENT OFFICE

NATHAN M. LOWER, OF PITTSBURGH, PENNSYLVANIA, ASSIGNOR, BY MESNE ASSIGNMENTS, TO THE STANDARD STOKER COMPANY INC., OF NEW YORK, N. Y., A CORPORATION OF DELAWARE

ROTARY ENGINE

Application filed September 7, 1923. Serial No. 661,370.

This invention relates to motors, and more particularly to the type in which a rotor is employed, having pressure blades associated therewith.

5 One of the objects of the invention is the production of new and improved mechanism for utilizing the expansive force of a fluid to maintain the pressure blades in fluid-tight contact with the walls of the casing on the 10 intake side of the motor during the operation of the device.

Another object of the invention is the provision of means whereby fluid pressure may be utilized for forcing the pressure blades 15 outwardly during the rotation of the rotor at low speeds, together with means for automatically closing the ports leading to the ends of the blades when the speed of the motor has increased to such an extent that 20 centrifugal force will cause sufficient pressure between the blades and the casing to prevent escape of the motive fluid at the ends of said blades during the operation of the motor.

25 Other and further objects and advantages of the invention will appear from the following description, taken in connection with the accompanying drawings, in which

Fig. 1 is a side elevation of the engine;

30 Fig. 2 is a longitudinal vertical section on line 2—2 of Fig. 1;

Fig. 3 is a transverse vertical section on line 3—3 of Fig. 2, the section of the casing being taken along the inlet and exhaust slots 35 31 and 32;

Fig. 4 is a portion of the view shown in Fig. 3, somewhat enlarged;

Fig. 5 is a section on line 5—5 of Fig. 7;

40 Fig. 6 is an enlarged section on line 6—6 of Fig. 2;

Fig. 7 is an enlarged detail showing a section of the power shaft with the parts assembled therein, with parts broken away;

45 Figs. 8 and 9 are vertical sections of a portion of the casing as viewed in opposite directions from the line 2—2 of Fig. 1; and

Fig. 10 is a perspective of a detail showing one end of the shaft 18 and parts associated therewith.

50 On the drawings, the reference character

10 designates a casing which may comprise the side plates 11 and 12 and the cylindrical member 13 clamped between said side plates as by means of suitable bolts 14. In order to form a fluid-proof joint between said plates and cylindrical member, the plates may be provided on their adjacent sides with curved ribs or lugs 15 and 16 which are adapted to telescope within the ends of the cylindrical member 13 when the parts are assembled. 55 These lugs are wider at one portion than at another, whereby recesses 17 are formed eccentric to the cylindrical member 13 for the reception of the wear plates of the rotor as will presently appear. 60

A power shaft 18 is eccentrically mounted in the casing 10 in any suitable manner. As shown, the shaft 18 is mounted in suitable anti-friction bearings 19 carried by the hubs 20 and 21 of the casing. 65

70 Keyed to the eccentrically mounted shaft 18 and adapted to rotate within the casing 10 is a rotor 22. The rotor engages the casing at one point only, as at the top thereby forming a crescent shaped chamber 23 between 75 the rotor and the said casing.

The rotor is provided with radial slots 24 which extend inwardly from the periphery of the rotor leaving an unslotted central or hub portion 25. Pressure blades 26 are slidably mounted in these slots. The sides of the slots may be closed by the wear plates 27 which are adapted to be secured to the ends of the rotor in any suitable manner. When the parts are assembled the wear plates engage in the recesses 17 formed by the lugs 15 and 16 in the plates 11 and 12. 85

90 Suitable inlet and exhaust ports are provided for permitting the entrance of the motive fluid to operate on the exposed sides of the outer ends of the pressure blades in the chamber 23 to rotate the rotor and to permit the exhaust of said fluid when its work has been accomplished. Any suitable ports may be provided for this purpose. As shown the 95 cylindrical member 13 is provided with chambers 28 and 29 at opposite sides of the casing. The port 31, leading from the intake chamber 28, is in the form of a short slot as shown in Fig. 8, while the slot 32 for the 100

exhaust may be considerably extended, as shown in Fig. 9. This arrangement permits the fluid at the intake side of the motor to act expansively and permits a free discharge of the fluid at the exhaust side of the motor. The slots are arranged diagonally in order that the wear on the ends of the pressure blades 26 shall be evenly distributed.

In the operation of the motor, when a blade 26 passes the lower end 33 of the slot 31 on the intake side of the motor the motive fluid acts directly on said blade to force the same downwardly until the next blade passes the lower end of the slot after which the 15 trapped fluid acts expansively to continue the downward movement of said blade.

It is necessary, especially at low speeds and during the starting period, that means be provided for forcing the blades outwardly 20 against the casing on the intake side of the motor. In order to reduce friction to a minimum and to simplify the construction it is desirable that fluid pressure be employed for this purpose instead of cams and the like as 25 is common in such constructions. One form of mechanism for accomplishing this function is illustrated in the drawings and will now be described.

The power shaft 18 is provided with a bore 30 18^a in one end thereof and in this bore is mounted a fixed pipe or conduit 34 having its inner end closed and provided with fixed parallel collars 35 and 36 spaced apart as shown in Fig. 7, to form a channel about the inner end of the conduit. Webs 37 and 38 divide this channel into an intake chamber 39 and an exhaust chamber 40. A sleeve valve 41 provided with inlet and exhaust ports 42 and 43 is non-rotatably but slidably mounted 40 on the pipe or conduit 34 for controlling the supply of steam or other fluid to the inner ends of the blades as will presently appear.

The hub portion 25 of the rotor is provided 45 with openings 44 which at their outer ends communicate with the slots 24 and at their inner ends register with corresponding openings or ports 45 in the hollow portion of the power shaft 18. The pipe or conduit 34 is provided with an inlet port 46 through which steam or other fluid under pressure may pass 50 into the intake chamber 39 and from thence through the port 42, openings 45 and 44 into the slots 24 in rear of the pressure blades 26 to force the same outwardly against the 55 interior of the intake side of the cylindrical member 13.

When the blades reach the exhaust side of the casing the steam or other fluid exhausts 60 from the slots 24 and openings 44 and 45 through the port 43 into the chamber 40 and from thence through openings 47 (see Figs. 5 and 7) in the collar 35 and through openings 48 in the valve 41 into the space surrounding 65 the pipe 34. From this space the fluid passes

into the atmosphere through suitable recesses 49 in the bushing 50 (see Figs. 2 and 6).

When the motor reaches a certain speed the centrifugal force will move the blades outwardly with sufficient pressure to prevent 70 leakage of the motive fluid without the aid of additional means for this purpose and without affecting the speed of the motor. At speeds above this any additional pressure for forcing the blades against the casing will detract from the efficiency of the engine. For 75 this reason suitable means are provided for automatically closing the intake port 46 when the motor reaches a predetermined speed. Any suitable means such as a centrifugal governor may be employed for this purpose. As shown, the valve 41 extends outwardly beyond the casing and is provided with a groove 51 in which pins 52 carried by the bifurcated ends of one of the bell crank levers 53 are 80 adapted to engage. These pins also engage slots in the inner ends of the other bell crank lever, as shown in dotted lines in Fig. 2. The levers 53 are pivoted to oppositely extending projections 54 carried by the end of the power 90 shaft 18. The free ends of the levers are provided with balls 55 which are adapted to be thrown outwardly by centrifugal force 95 against the tension of springs 56 as is usual in such constructions.

In the operation of the device, the rotation of the shaft will cause the balls 55 to swing outwardly and move the sleeve or valve 41 axially outwardly and thus close the port 42. The exhaust port 43 is considerably wider than the intake port 42 and consequently the 100 exhaust port remains open at all times.

Suitable oiling systems 57 and 58 are employed in connection with the intake pipes 280 and 34 for lubricating the rotor, blades 105 and the like, but since these are of the usual or well known type, it is not thought necessary to describe the same in detail.

Glands 59 or other suitable packing may be employed to prevent the escape of the motive fluid into the rotor bearings. The inner wall of the side plates 11 and 12 may be provided with grooves 60 having outlet ports 61 for conducting the motive fluid, escaping between the rotor and the plates, from the 115 motor.

While the motor is adapted to operate with steam as a motive fluid it is understood that any suitable fluid may be employed for operating the same.

I claim as my invention:

1. In combination, a cylindrical casing, a rotor eccentrically mounted in said casing and provided with slots, blades slidably mounted in said slots, a port in said casing for admitting an expansive fluid into said casing for operating against the side faces of said blades for rotating said rotor, means independent of said port extending axially of said rotor for admitting an expansive fluid 125 130

- to operate against the inner ends of said blades to force the same outwardly into engagement with said casing during the time pressure is being applied to their side faces, and means for automatically controlling the passage of said fluid through said means independently of the passage of fluid through said port. 5
2. In a rotary engine, a casing, a rotor mounted for rotation within said casing, blades slidably mounted within said rotor, a port for admitting a fluid under pressure into said casing to operate on the side faces of said blades, a port for admitting a fluid under pressure into said casing for forcing said blades outwardly, and means for automatically closing said last named port only, when the engine has reached a predetermined speed. 10
3. A rotary engine comprising, in combination, a cylindrical casing, a rotor mounted therein, radial pressure blades slidably carried by the rotor and engageable with the cylindrical wall of the casing, means for applying fluid pressure to the faces of the blades, means independent of said first-named means for applying fluid pressure to the inner ends of said blades in an outward radial direction, and means for independently and automatically cutting off the supply of said fluid to said blades. 20
4. In combination, a casing, a rotor eccentrically mounted within said casing, pressure blades slidably mounted in said rotor for rotat- 35
- ing the same, including fluid pressure for forcing said blades outwardly against said casing while passing through a certain zone in their rotation, and means for rendering said fluid pressure ineffective for moving said blades while the same are passing through another zone in their rotation, said means comprising an axial passage in the axis of said rotor, said passage being provided with inlet and exhaust ports, and means for automatically opening and closing said ports. 40
5. In combination, a casing provided with diagonally arranged intake and exhaust ports, a rotor mounted in said casing and provided with slots, blades slidably mounted in said slots, means for utilizing a motive fluid for rotating said rotor and for forcing said blades outward against said casing on the intake side of said casing, and means for automatically controlling the amount of said fluid utilized to force said blades outwardly, independently of the amount of said fluid utilized for rotating said rotor. 55
6. In combination, a casing, a shaft eccentrically mounted in said casing and adapted to rotate therein; a rotor secured to said shaft, and provided with slots, blades slidably mounted in said slots, means for applying a motive fluid to the sides of said blades, means independent of said first-named means and including a stationary conduit located 60
- in said shaft and provided with ports for applying a fluid under pressure to the ends of said blades on the intake side of said casing, means including a sleeve slidably mounted on said conduit and having ports therein for exhausting said fluid from the opposite side of said casing, and a centrifugal governor for automatically adjusting said sleeve. 70
7. In combination, a casing, a shaft rotatably mounted in said casing, a rotor mounted on said shaft and provided with radial slots, blades in said slots, means for applying pressure to the sides of said blades, a stationary conduit extending into said shaft, a port associated with said shaft and in communication with said conduit, and adapted to communicate with said slots during the rotation of said rotor, a valve for said port and a centrifugal governor mechanism for moving said valve for controlling the opening and closing of said port. 75
8. In a motor, a casing, a rotor rotatably mounted in said casing, said rotor provided with slots therein, pressure blades slidably mounted in said slots, and adapted to engage said casing, and means for introducing a fluid under pressure through the periphery of said casing for applying fluid pressure to the side faces of said blades, means for introducing a fluid under pressure into the interior of said casing for applying fluid pressure to the inner ends of said blades during a portion only of the rotation of said rotor, and means for automatically controlling said last-named means. 80
